UNITED STATES PATENT OFFICE.

CHARLES T. RASCHICK, OF ST. PAUL, MINNESOTA.

TICKET HOLDER AND CUTTER.

Application filed January 10, 1921. Serial No. 436,093.

To all whom it may concern:

Be it known that I, CHARLES T. RASCHICK, a citizen of the United States, residing at St. Paul, in the county of Ramsey and State of Minnesota, have invented a new and useful Improvement in Ticket Holders and Cutters, of which the following is a specification.

My invention relates to a device for holding detachable sales checks such as are used in restaurants and various other places where the waiter is required to tear off the check from its stub and give the customer the severed section on which the amount of the purchase is indicated.

The invention provides a shearing device for cutting notches in the edge of the check to indicate the amount of the purchase. An essential feature of the invention consists in the construction of the shearing device and the arrangement of the parts thereof so as to form a guard for the pointed end of the shearing tongue in order that no portion will be exposed upon which anyone is liable to be injured.

It is also an object to provide a holder for checks which will be simple in construction and which may be stamped out of a single piece of sheet metal and which can be conveniently fastened to the waist band or belt of the user in a manner to be readily reached when necessary to detach the check.

In the drawings, illustrating the application of my invention in one form:—

Fig. 1 is a plan view of a check holder embodying my invention showing a book of checks held thereby.

Fig. 2 is a side elevation of the same.

Fig. 3 is a bottom view of the holder.

Fig. 4 is a transverse section on the line 4—4 of Fig. 3.

Fig. 5 is a longitudinal vertical section showing the tongue in cutting position and also showing a check which has been notched along its edge.

Fig. 6 is a longitudinal vertical section showing the manner of inserting the book of checks underneath the holding means for retaining the book upon the holder.

Fig. 7 is a perspective view showing the top leaves of the pad folded back and the ends of the bottom leaves inserted beneath the pad supporting means on the holder.

In the drawings, A illustrates the holder generally and B a pad of checks supported by the holder. The book or pad of checks which the holder is designed to support consists of a series of checks 10 bound together by a staple 11 passing through the stub ends of the same. On the face of each check is printed a series of price marks adapted to be notched out for the purpose of indicating the amount of the sale.

The holder A comprises a base plate 12, of such length as to support the pad of checks. The longitudinal side edges of the plate 12 are bent to form upstanding flanges 13 extending the length of the base plate to provide means for stiffening the base plate and also to facilitate the proper positioning of the tickets on the base plate.

The upper end of the holder A is provided with means for retaining the pad upon the holder, consisting of a bar or strip 14 formed integral with the base and extending between the flanges 13, parallel to and spaced above the base plate 12. The bar 14 is adapted to receive a few of the leaves 27 of the pad B so as to snugly engage beneath the strip 14 to hold the pad of checks B firmly in place.

The pad to be retained upon the holder consists of a series of checks bound together by a staple 11 passing through the stub end of the same. The pad is placed in position by having the free ends of a sufficient number of the bottom leaves 27 inserted beneath the bar 14 as shown in Fig. 7, and the pad is moved along the holder until the bar engages the stitching 11 at the stub end of the pad, any downward bodily movement of the pad being prevented by the stitching 11. A sufficient number of leaves are inserted beneath the bar 14 so that the pad is retained with sufficient force to prevent the accidental displacement of the same but will yield to force when required to be withdrawn. Thus the pad is securely held in position and yet the checks may be readily detached therefrom.

The flanges 13 are preferably provided with suitable guiding members 15 cooperating with the checks 27.

The guide members 15 project inwardly at right angles to the flanges 13 and are spaced the same distance above the base

plate 12 as the support 14, being positioned a short distance in front of the support 14. In placing the pad in place upon the holder the free ends of the bottom leaves 27 are 5 first passed underneath the guide members 15 to maintain them in proper alignment with the base plate 12 in passing underneath the support 14 so as to prevent the ends of the checks from going through the 10 aperture 26 in the space underneath the support 14 from which the support was cut, as shown in Figures 2, 5 and 6.

The lower end of the base plate is provided with a shearing device for notching 15 the edges of the checks to indicate the amount of the purchase, said means consisting of a tongue 16 stamped from the body portion of the base plate 12 and extending therefrom as an integral part of the base 20 plate. The tongue 16 is curved slightly downward and has an upwardly extending portion 17 which extends through a slot 18 in the base plate from which the tongue is cut, as shown in Fig. 6, and terminating in 25 a pointed end 19 having cutting edges 20 which cooperate with the cutting edges 21 formed in the angularly disposed portion 22 of the base plate 12. The portion 17 of the tongue is angularly positioned relative 30 to the inclined member 22 as best shown in Figs. 2 and 6 so that the pointed end 19 will first pierce the check when the tongue is pressed downwardly, whereby a shearing action is given to the tongue as the cooperating 35 edges are successively brought together.

The check holder A is formed from a single piece of material and this is an important feature of my invention, as the body portion forms the back for a pad of checks B while 40 one end of the holder is so formed as to provide means for cutting or notching the edge of a check, the cutting tongue of which is formed from the material of the holder, being centrally positioned in a manner so that 45 it is operable to notch the edge of a check by inserting the edge of the check beneath the pointed end of the cutting member and depressing the free ends of the pad of checks upon the holder, as is illustrated in Fig. 5. 50 The cutting means of the holder, in the form shown, is adapted to cut a V-shaped notch on the edge of the check to indicate the amount of the purchase when the check is issued. The free ends of the checks 10 are 55 held in a slightly raised position by the cutting tongue 16 when the same is in normal position. The cutting means are operable to first pierce the body of the check and then shear towards the edge, thus providing a 60 simple and very effective cutting means in the holder itself without the necessity of providing a cutter which requires sharpening from time to time, the nature and construction of this cutter is such that it will readily

operate to cut a notch in the check by a 65 piercing and shearing action which does not have a tendency to dull the cutter as is true with the ordinary punching means.

The peculiar construction of the large body portion of the tongue 16, which is 70 sheared from the body of the holder without weakening the back of the holder, provides sufficient resiliency in the tongue to hold it elevated above the cutting edges 21 formed in the angularly disposed portion 22 while 75 the tongue is curved in a manner to cause it to normally position itself above the cutting edges 21 in readiness for operation, holding the free ends of the checks 10 slightly elevated, which are engaged and depressed to 80 operate the tongue. This construction provides a very practical check cutting means, the cutter being fully protected to prevent the user from being injured while carrying the same.

The member 21 is provided with gage 85 stops 23 for the checks, for limiting the depth of the cut of the tongue 16. Said stops are stamped from the inclined member 90 22 and are positioned adjacent the sides and near the pointed end 19 of the tongue. These stops perform a double function, being adapted to form abutments for the lower end 95 of the pad of checks to prevent any downward movement of the same, as clearly shown in Figs. 2 and 5.

When the tongue 16 is returned to its normal position the pointed end is positioned between the stops 23 and the inclined member 22 so that the same will protect the sharp 100 end of the tongue in order that no portions thereof will be exposed upon which the operator can be accidentally injured from contact therewith.

The upper end of the base plate 12 is 105 formed with an aperture 25 by means of which it may be attached to a hook 24 for carrying the same by the user so as to be ready at hand when needed.

The simplicity of the design of my holder together with the practical nature of the same provides a very desirable check holder and cutting means formed from a single 110 piece of material which can be manufactured at a reasonable cost.

I claim:

1. A device of the class described formed from a single piece of sheet metal, comprising a cutter, a shearing tongue formed from the body of said device and cooperating with a member formed on said device, inclined upwardly therefrom to form shearing means, said inclined member extending in front of said tongue when in released position to provide a guard to conceal the same.

2. A ticket shearing device comprising a base plate, a shearing tongue projecting above said plate having a pointed end

formed with cutting edges, and a member extending upwardly at an oblique angle having a notch formed with cutting edges with which the end of the tongue is adapted 5 to cooperate to form a shearing device.

3. A device of the class described including a ticket notching means formed from sheet material comprising a cutting tongue

and an angularly disposed portion extending in front of said tongue and being provided 10 with shearing edges to cause said tongue to cut with a shearing action, and said angularly disposed portion provided with guard means in front of the point of said cutter.

CHARLES T. RASCHICK.
